Des. 238,906

Patented Feb. 17, 1976

238,906

INFANT FEEDING BOTTLE

Richard E. Cone II, 249 Bowman Drive,
Kent, Ohio 44240

Filed Oct. 16, 1974, Ser. No. 515,180

Term of patent 14 years

Int. Cl. D7—01

U.S. Cl. D83—8 A

FIG. 1

FIG. 2

FIG. 3

FIG. 4

FIG. 5

FIG. 1 is a front elevation of an infant feeding bottle showing my new design;

FIG. 2 is a right side elevation thereof;

FIG. 3 is a rear elevation thereof;

FIG. 4 is a top plan view thereof; and

FIG. 5 is a bottom plan view thereof.

I claim:

The ornamental design for an infant feeding bottle, as shown.
